Alfred Walker,
By Atty. Inventor
John S. Clark

UNITED STATES PATENT OFFICE.

ALFRED WALKER, OF NEW HAVEN, CONNECTICUT.

IMPROVEMENT IN DICE-BOXES.

Specification forming part of Letters Patent No. **171,707**, dated January 4, 1876; application filed November 16, 1875.

To all whom it may concern:

Be it known that I, ALFRED WALKER, of New Haven, in the county of New Haven and State of Connecticut, have invented a new Improvement in Dice-Boxes; and I do hereby declare the following, when taken in connection with the accompanying drawings and the letters of reference marked theron, to be a full, clear, and exact description of the same, and which said drawings constitute part of this specification, and represent, in—

Figure 1, perspective view; Fig. 2, vertical central section; Fig. 3, one of the wires detached; Fig. 4, the binding-ring detached.

This invention relates to an improvement in boxes for throwing dice, the object being to constantly retain the dice in the box, and yet allow the necessary shaking and properly expose the dice when set; and it consists in a pair of flat disks, forming two heads, connected by an open-work casing, whereby the box may be set upon either head and the dice exposed on the lower head, and so that simply inverting the box to throw the dice to the other head will give the necessary agitation, as more fully hereinafter described.

A is one disk or head, and B the other. These heads are connected by wires *a*, the ends *d* turned inward, so as to be set into corresponding perforations in the respective heads or disks. These wires are made substantially straight, as seen in Fig. 3, and after one end has been inserted into its disk, a ring, C, preferably of less, but may be the same diameter of the disks, is placed over the wires to the center, and then the other head placed in position, the ends of the wire at this end inserted into their

proper relative position or respective perforations in the head. The ring C, being smaller, contracts or springs inward the wires, so as to freely bind them in position, and thus secure the heads together, and give to the box substantially the form of the common dice-box. These wires expose the dice within the box, which it will be understood are placed there before the last head is set. The box may be shaken in the usual manner for shaking dice boxes to agitate the dice, and when set or held in a vertical position the dice will be exposed on the lower head, so as to be clearly seen through the sides, and by simply inverting the box, so as to throw the dice to the opposite end, sufficient agitation will be given to the dice in falling from one head to the other.

While preferring a series of wires for the sides of the box, other material capable of similar attachment may be used.

I claim—

1. A dice-box consisting of the two flat disks or heads A B, connected by an open-work case arranged to expose the dice on either head, according to the position in which the box is set, as set forth.
2. The two disks or heads A B, connected by a series of vertical wires or rods, *a*, the ends of which are turned into corresponding perforations in said heads, and combined with the securing or encircling ring C, substantially as described.

ALFRED WALKER.
